UNITED STATES PATENT OFFICE.

CHARLES GOODCHILD, OF OAKLAND, CALIFORNIA, ASSIGNOR OF ONE-HALF TO JOHN J. McGINLEY, OF OAKLAND, CALIFORNIA.

MEANS FOR HOLDING THE STATIONARY ELEMENT OF A COASTER BRAKE.

Application filed April 7, 1921. Serial No. 459,841.

To all whom it may concern:

Be it known that I, CHARLES GOODCHILD, a citizen of the United States, and a resident of Oakland, county of Alameda and State 5 of California, have invented a new and useful Means for Holding the Stationary Element of a Coaster Brake, of which the following is a specification.

My invention relates to means for fastening the stationary element of a coaster brake 10 such as is used on bicycles or the like, to the frame of the vehicle.

An object of the invention is to provide means of the character described which are 15 both effective and unobtrusive.

Another object of the invention is to provide means of the character described which will prevent the spreading of the fork tips 20 of the vehicle frame.

A further object is to enable the device to be readily attached to known types of 25 coaster brakes.

The invention possesses other objects and features of advantage, some of which, with 30 the foregoing, will be set forth in the following description of the preferred form of my invention which is illustrated in the drawings accompanying and forming part 35 of the specification. It is to be understood that I do not limit myself to the showing made by the said drawings and description, as I may adopt variations of the preferred form within the scope of my invention as 40 set forth in the claims.

Referring to said drawings:

Figure 1 is a side elevation of a coaster 45 brake equipped with the holding means of my invention, part of the structure being broken away and shown in section to dis- close the hidden parts more clearly.

Figure 2 is an end view of the structure including a portion of the vehicle frame.

Figure 3 is a perspective view of the holding means.

Figure 4 is a side elevation of a slightly modified construction.

The device is here illustrated in connection with a well known type of coaster 50 brake, but it is to be understood that the principle involved in the means of my invention may be readily incorporated with other types. As here shown the structure comprises a coaster brake 2 in which is contained the brake element 3 that is adapted 55 to expand against the opposing brake ele-

ment 4 formed by the inner face of the hub shell 6. As the shell 6 is the rotating element, means must be provided for holding the element 3 against rotation so that when the latter is expanded the proper friction 60 between both elements may be provided. In the type of brake illustrated in the drawings the element 3 is secured to the bearing cone 8 and the latter is adapted to be fastened to the frame 9 of the vehicle, thereby causing the element 3 to be held stationary. The exposed end 11 of the cone is usually 65 formed with a ratchet face 12, which prior to the present invention, was adapted to be rigidly clamped and locked against the fork tips 13 and 14 of the vehicle frame 9 by the nut 16 which engages the threaded end 18 of the wheel axle 19. Since when the brake is functioning, the turning effort of the cone 70 is considerable, a slight looseness of the cone 75 will cause it to turn, thus causing the ratchet teeth to gradually but continually cut away the inner face of the fork tips. In accordance with my invention the foregoing 80 feature is eliminated, the tips being prevented from becoming mutilated, and the cone at the same time held effectively locked thereto. In the preferred embodiment I provide a retaining member or plate 21 which is formed with a central aperture 22 85 so that the plate may be slipped over the axle. The plate is arranged to be interposed between the fork tips and the cone, one side of the plate being formed with a ratchet face 24 which corresponds to and is ar- 90 ranged to engage the ratchet face of the cone. Extending outwardly from the opposite edges of the plate is a pair of arms 26 which are arranged to straddle the tips and thereby lock the plate and consequently the 95 cone and element 3 against rotation. The arms are comparatively small and when the nut clamps the tips against the plate the end of the arms lie about flush with the outer surface of the tips; it will thus be seen that the 100 plate together with the arms are very inconspicuous.

Since the arms are arranged to tightly overlie or straddle both tips, the latter although being separated at one end, are prevented from spreading even when subjected to extremely rough usage.

In Figure 4, I have shown a slightly modified construction. In this embodiment the arms are formed integral with the cone 110

thereby eliminating the necessity of a separate plate.

I claim:

1. In a device of the class described, a member adapted to be fixed to the stationary brake element of a coaster brake and arranged to be pressed against the inner face of the tips of one of the rear fork legs of the vehicle frame, and a pair of oppositely disposed outwardly extending arms provided on said member adapted to fit over and engage the outer edges of said tips.
2. In a device of the class described, a perforated member adapted to be mounted upon the wheel axle and arranged to lie between the inner face of the tips of one of the fork legs of the vehicle frame and the ratchet face of one of the fixed elements of the brake, a ratchet face on one side of said member adapted to engage the ratchet face

of said element, and a pair of arms extending outwardly from the other face of said member adapted to engage the outer edges of said tips and arranged to terminate at 25 the outer face of the tips.

3. In a device of the character described, a perforated member adapted to be mounted on the wheel axle and arranged to lie between the inner face of the tips of one of the fork legs of the vehicle frame and one of the elements of the brake, a knurled face on one side of said member adapted to engage the adjacent face of said element, and a pair of arms extending outwardly from 30 the other face of said member adapted to engage the outer edges of said tips.

In testimony whereof, I have hereunto set my hand at Oakland, Calif., this 28th day of March, 1921.

CHARLES GOODCHILD.
